(57) **CLAIM**

The ornamental design for a credit card, as shown and described.

DESCRIPTION

FIG. 1 is a top view of the credit card with a hole for attachment to a key chain showing a first embodiment of the present invention;

FIG. 2 is a bottom view of the credit card of FIG. 1; FIG. 3 is a side view of the credit card of FIG. 1 as seen from the left-hand side of FIG. 1;

FIG. 4 is a side view of the credit card of FIG. 1 as seen from the right-hand side of FIG. 1;

FIG. 5 is a top view of the credit card illustrating the location of the credit card number, cardholder's name and company logo; and,

FIG. 6 is a bottom view of the credit card illustrating the location of the magnetic strip and cardholder's signature box.

The broken lines in FIGS. 5 and 6 are for illustrative purposes only and form no part of the claimed design.
